Inventor:
Max Kassap,

By his Attorney, Leo. W. Matz

UNITED STATES PATENT OFFICE.

MAX KASSAP, OF BROOKLYN, NEW YORK.

MASCULINE UNDERWEAR.

Application filed November 14, 1925. Serial No. 68,944.

The object of my invention is the production of a unitary structure of an under garment for masculine wear adapted to the health, convenience, and comfort of the individual using same; and the invention consists essentially in the formation, combination, and arrangement of component parts of the garment, shown and described and claimed specifically, whereby these and other 10 advantageous results are attained as herein-after fully set forth.

In the accompanying drawings I illustrate a practical embodiment of the essential features of my invention in an under 15 garment of the character designated, although I do not limit myself to the identical configuration of component parts thereof shown by way of exemplification, since modifications may be resorted to in minor 20 details with like results, and without departing from the spirit and intent of my invention in this respect.

With this understanding:—

Fig. 1, is a front view of my new garment; 25 and

Fig. 2, a rear view thereof;

Fig. 3, is a view similar to Fig. 2, broken away in part, and showing the posterior portion of the garment unbuttoned and opened 30 up;

Fig. 4, is a sectional detail taken upon plane of line 4—4, Fig. 2.

My unitary underwear garment consists essentially of frontal sections F, F, connected medially by detachable means, (as by buttons and button holes b, Fig. 1) and of combined full length and width including the fronts f, f, of the leg portions; of a back section B, and of a posterior section P.

40 The shoulder portions a, a, of both the frontal sections F, F, and the back section B, above the arm holes a', a', are seam-connected, as are also the sides of the said frontal section and back section B, as indicated at s, s, in the drawings.

45 The posterior section P, of the garment, constituting the seat and the rear portions of the legs thereof, is formed of two pieces united medially at p, and to the sides of the frontal section F, as at p', p'. It is also formed with a waist band w, which is at-

tached at each of its extremities to the frontal section F; said waist band containing a strip e, of elastic resilient material which tends constantly to contract said waist band 55 and the adjacent portion of the posterior section P, and to draw the waist portions of the frontal sections F, F, taut over the abdomen of the wearer.

The back section B, of the garment is 60 formed with a transverse insert strip i, of flexible elastic-weave material, (as for instance that known technically as Jersey cloth) or the equivalent thereof, the other body portions of the garment consisting of 65 linen or other suitable texture material, as may be found most expedient. The lower portion B', of the back section B, below the flexible insert strip i, extends below the normal position of the waist band w, (shown in 70 Fig. 2) and is provided with buttons b', b', for engagement with button holes w', w', formed for the purpose in the waist band w. Or, obviously, if preferred, hooks and eyes, or equivalent detachable means may be 75 provided connecting the waist band w and lower portion B', of the back section B, with like results,—the object in this respect being to provide for the temporary lowering 80 of the upper portion of the posterior section P, of the garment as indicated in Fig. 3, of the drawings upon occasion.

The insert i, of flexible elastic weave is 85 yieldable to strain of wear and conducive of comfort to the wearer, and in conjunction with the elastic resilient waist band w, insures a close fit of the garment where most desirable.

What I claim as my invention and desire 90 to secure by Letters Patent, is:—

As an improved article of manufacture, a unitary garment of the character described, comprising frontal sections, an upper back section, said frontal sections being secured at the edges to said back section, a posterior section consisting of two parts joined permanent medially and to the side edges of the frontal section, and an elastic resilient waist band permanently secured to the side edges of the frontal section, the 100 transverse extent of the combined parts of the said posterior section being consider-

ably greater than the transverse extent of the upper back section, whereby fullness is provided in the posterior section permitting lowering thereof without detachment at the 5 side edges, the said waist band being secured to the top of the posterior section and adapted to hold the posterior section snug-

ly against the back of the wearer and in overlapping relation to said upper back section, and means detachably connecting said 10 waist band with the lower portion of the upper back section.

MAX KASSAP.
